DESIGN FOR A PERFORATE PROTECTOR PLATE FOR DISPLAY CARDS

Edward Sonin, Long Beach, N. Y.

Application March 11, 1938, Serial No. 75,756

Term of patent 14 years

To all whom it may concern:

Be it known that I, Edward Sonin, a citizen of the United States, residing at Long Beach, in the county of Nassau and State of New York, have invented a new, original, and ornamental Design for a Perforate Protector Plate for Display Cards, of which the following is a specification, reference being had to the accompanying drawing, forming part thereof.

Figure 1 is a plan view of a perforate protector plate for display cards, showing my new design.

Figure 2 is a transverse sectional view taken on line 2—2 of Figure 1.

I claim:

The ornamental design for a perforate protector plate for display cards as shown.

EDWARD SONIN.
